(57) **CLAIM**

The ornamental design for a palm-shaped pillow, as shown and described.

DESCRIPTION

FIG. 1 is a top perspective view of a palm-shaped pillow, showing our design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof.

FIG. 7 is a bottom plan view thereof; and,

FIG. 8 is perspective view of the palm-shaped pillow in a use state.

The broken lines in the drawings depict environmental structure and boundaries and form no part of the claimed design.

(Continued)

The symbolic break lines depict the boundaries of the claim. The area between the break lines forms no part of the claimed design.
